TELEGRAPH KEY

Hans E. Trømholt, Bayside, Long Island, N. Y.

Application October 15, 1942, Serial No. 462,099

2 Claims. (Cl. 178—101)

This invention relates to telegraph keys and particularly it refers to a key of such construction that the noise generated by the operation of same is reduced to a point below the audible level.

Telegraph keys belong to an old and well developed art. Nevertheless, they have had certain faults, which it has not heretofore been possible to eliminate. One of these faults or disadvantages of the ordinary telegraph keys is to be found in their usually noisy operation. By noisy operation is meant the clicking mechanical sound generated by the rapid manual operation of the key. Most commercially available keys make such a loud noise that they can easily be heard from one room to the next and it was found in the last war that quite often spies would listen in on secret telegraphic dispatches merely by listening to the noise of the keys from an adjoining room. Another difficulty has been due to the fact that keys ordinarily have not been electrically insulated so that the operator would receive shocks from the handle bar in thunder storms and when, for instance, accidentally some high voltage were introduced in the telegraph circuit. In my present invention I have eliminated this situation and I have provided a key which is electrically insulated and nearly noiseless, or which in technical terms may be said to have had its noise level reduced to below the audible minimum. This audible minimum is also often designated as the threshold of hearing, which is the noise level at which a normal human ear can no longer distinguish a given sound.

The object of my invention is, therefore, to provide a noiseless telegraph key. Another object of my invention is to provide a key which is compact, light, dependable in operation, and low in cost.

Other objects and advantages of my invention will be apparent during the course of the following description:

In the accompanying drawings, forming a part of this specification, and in which like numerals are employed to designate like parts throughout,

Figure 1 is a plan view of a telegraph key embodying my invention,

Figure 2 is a side elevation of the key shown in Figure 1,

Figure 3 is an end elevation of the same key,

Figure 4 is a section taken along line 4—4 in Figure 1, and,

Figure 5 is a section taken along line 5—5 in Figure 2.

In the drawings, wherein for the purpose of il-

lustration, is shown a preferred embodiment of my invention, the numeral 10 designates the knob, which is mounted on the arm 11. The arm 11 is provided with a transverse shaft 12, which is pivoted in two bearings 13 in the U-shaped bracket 14, which is mounted on the base 15. The arm 11 furthermore is provided with an adjustable screw 16, which has a lock nut 17 and a spring 18, which is recessed in base 15. The spring 18 serves to hold the arm 11 in the upward position at all times except when pressed downward by the operator by placing his hand on knob 10. The U-shaped bracket 14 is mounted to base 15 by means of counter-bored screws 19. The hole in base 15 in which screws 19 are placed is afterwards filled in with insulating compound.

The base 15 has a plurality of mounting holes 20 and is also acting as the support for the terminals 21 and 22, which are normally the input terminals in a single circuit key. The arm 11 which carries the knob 10 at one end carries at its other end the metal member 23, which is electrically insulated from arm 11 by means of insulated strips 24 and insulating tubings 25. The member 23 is fastened to arm 11 by means of screws 26 and 27, see Figure 4. Screw 26 extends through the member 23 and is furnished with nut 28 under which is placed the soldering terminal 29, which is electrically connected by means of the flexible wire 30 to the input terminal 21. The outer end of the metallic member 23 carries the electrical contact 31, which extend through said member 23 and has a contact surface on both sides of same. The contact member 31 in its normal, non-operative position, makes contact with the lower contact screw 32, which is fastened in the base 15 by means of nut 33, see Figure 4.

At one end of the base 15 is mounted the Z-shaped bracket 34, which carries the upper contact screw 35 with the contact point 36. The screw 35 is adjustable in the bracket 34 by means of lock nut 37. Bracket 34 is mounted to the base 15 by means of screw 38, the upper end of which is furnished with nut 39, under which is fastened soldering terminal 22, see Figure 3.

The life and satisfactory operation of the key is depending to a considerable extent upon the bearings 13 and the transverse shaft 12. It should be noted, therefore, that the shaft 12 is pinned to the arm 11 by means of pin 40 and the shaft 12 is usually made from phosphor bronze or other suitable material, while the bearings 13 may be either stainless steel or may be ball

bearings. This construction will greatly increase the useful life of the key and will prevent same from wearing and becoming loose and unreliable in operation. It should, furthermore, be noted that with this construction it is not necessary to adjust the bearings as is usually required by the heretofore commonly used telegraph keys, which in most cases have pivot type bearings.

The operation of my invention is as follows:

In using the present key, the connections are made to terminals 21 and 22 in the usual manner. The contact adjustment screw 35 is adjusted to give the minimum required gap between the contact point 36 and the contact 31 of the member 23. After the screw 35 has been once adjusted it is locked in place by the lock nut 37 and will not have to be adjusted again for a long time depending upon the service for which the key is intended. In continuous service it is obvious that the contacts 36 and 31 will eventually become slightly pitted and worn from the electric arc and at intervals, usually months apart, it may become necessary to clean these contact points and readjust the screw 35.

The actual manual operation of the key is almost exactly similar to the operation of any other telegraph key and will not, therefore, be further described. The operation of my invention, however, depends upon the fact that the metallic member 23 has been insulated both electrically and acoustically from the arm 11. By acoustical insulation is meant that the insulating parts 24 and the tubular members 25 are placed in such a manner and are selected of such materials that audible vibrations generated by the clicking of the contacts 31 and 36 will not be transmitted from the member 23 to the arm 11. It is a well-known fact that sound or in more technical language, acoustic vibrations, will travel through metals at very high speeds and depending upon the frequency of the sound transmitted, the vibrations may excite the metal parts into forced vibrations of a similar or harmonic frequency. It is well-known too that every structural part, regardless whether same is made from metal or other elastic material, has a certain natural frequency which is usually called its resonant frequency and at which it will vibrate violently if excited. When a sound wave is transmitted through an elastic body, such as a metal part it will travel at great speed until it hits a boundary medium. At this point it will set up what is usually called an acoustic impedance, which may be very great depending upon the nature of the boundary medium. This acoustic impedance will usually transmit a small part of the on-coming sound wave, while the rest of the wave will be reflected back toward its origin. By applying the correct acoustic insulation, therefore, to obtain an acoustic impedance of a suitable magnitude, the sound wave may be reflected in its entirety and no transmission of same will result. In this event, the sound will travel back and forth and will dissipate itself in the form of heat. In the event, however, that the member through which the sound wave is travelling has a resonant frequency inside of the range of the sound wave or its harmonics, the member may be excited into forced vibrations of an audible character. To avoid this it is only necessary to design a member of such physical size and characteris-

tics that its natural frequency will be far removed from the range of any sound or its harmonics.

The above is the theory underlying the functioning of my present invention, in which I have insulated the member 23 acoustically from the arm 11. The member 23 is of small dimensions and of a considerable cross section as compared to its length. The natural frequency of the member 23, therefore, will be very high and will be far removed from the frequency of the sound created by the banging of contacts 31 and 36. The member 23 is, furthermore, clamped by the screw 26 and 27 in such a manner that it could only vibrate with its free end, which is very short. To prevent the transmission of any sound waves from the member 23 to the arm 11 and to other parts connected with same, I have provided the insulation 24 and 25, which effectively provides a high acoustic impedance, stopping any sound waves generated in member 23. By selecting the insulation 24 and 25 from suitable material, such as fibre, Bakelite, or other fibrous substances, I can thereby prevent the transmission of any sounds from the member 23 to the other parts of the key, particularly to the arm 11, which would naturally have a fairly low resonant frequency and would be able to carry out audible vibrations if so excited.

It is to be understood that the form of my invention, herewith shown and described, is to be taken as a preferred example of the same and that various changes in the shape, size, and arrangement of parts may be resorted to, without departing from the spirit of my invention or the scope of the subjoined claims.

Having thus described my invention I claim:

1. A telegraph key of the character described, comprising a base; a bearing support mounted on said base, a plurality of bearings mounted in said bearing support; an arm pivoted intermediate of its ends in said bearings and having a knob mounted on one end; a contact making member fastened to the other end of said arm, said contacting making member being straight, short and rigid and projecting a small distance from the end of said arm and having a considerable cross section as compared to its length, whereby same will have a high natural vibrating frequency, and acoustical insulation placed between said contact making member and said arm, whereby audible vibrations created in said member may be dissipated in same without being transmitted to said arm.

2. A telegraph key of the character described, comprising a pivoted arm having a knob at one end; a contact making member fastened to and projecting slightly from the other end of said arm, said contact making member being short and rigid and attached by more than one point to said arm and said points of attachment being longitudinally of said arm and tending to give said contact making member a high natural vibration frequency, and acoustical and electrical insulation provided between said contact making member and said arm, whereby sounds generated in said contact making member may be confined to and dissipated in same without being transmitted as audible vibrations.

HANS E. TROMHOLT.
